Primary Examiner — Kelley A Donnelly*(74) Attorney, Agent, or Firm* — Knobbe, Martens, Olson & Bear, LLP(57) **CLAIM**

The ornamental design for a display box assembly, as shown and described.

DESCRIPTION

FIG. 1 is a top-front-right perspective view of a display box assembly, according to my new design;

FIG. 2 is front elevational view thereof;

FIG. 3 is a rear elevational view thereof;

FIG. 4 is a right side elevational view thereof, a left side elevational view being a mirror image of the right side elevational view;

FIG. 5 is a top plan view thereof, a bottom plan view being identical thereto;

FIG. 6 is a top-front-right perspective view of an inner framework of the display box assembly, which is visible inside the display box assembly in use;

FIG. 7 is an exploded view of an outer cladding of the display box assembly; and,

FIG. 8 is a top-front-right perspective view of the outer cladding, assembled without the inner framework.

Broken lines are used in the views to depict features which form no part of the claimed design, including environmental features showing the display box assembly in use and a front edge shape of side walls of the outer cladding.

1 Claim, 7 Drawing Sheets(56)
